UNITED STATES PATENT OFFICE.

FRED W. TOBEY, OF CINCINNATI, OHIO, ASSIGNOR TO THE GLOBE-WERNICKE COMPANY, OF CINCINNATI, OHIO, A CORPORATION OF OHIO.

LETTER-FILE.

SPECIFICATION forming part of Letters Patent No. 716,148, dated December 16, 1902.

Application filed December 20, 1901. Serial No. 86,657. (No model.)

To all whom it may concern:

Be it known that I, FRED W. TOBEY, a citizen of the United States, residing at Cincinnati, in the county of Hamilton and State of Ohio, have invented certain new and useful Improvements in Letter-Files, of which the following is a full, clear, and exact description, reference being had to the accompanying drawings, forming part of this specification.

My invention relates to that class of drawer or tray files composed of a bottom piece, a front wall, and two side walls, the back end being left open and the whole being intended for use as a temporary binder to be left loose upon a desk or to be slipped into a drawer-compartment in a cabinet, as desired. This class of files is usually provided with a spring bail-piece hinged to the back and adapted to be automatically pressed down upon the contents of the file at or near the middle of the same and which bail can be raised whenever it is desired to gain access to or remove or replace the contents of the file; and it has for its object the provision of novel mechanism by which the spring-bail is secured to and actuated upon the file, whereby simplicity of construction, durability, and efficiency of action are attained.

The novelty of my invention will be hereinafter more fully set forth, and specifically pointed out in the claim.

In the accompanying drawings, Figure 1 is a sectional side elevation of a file embodying my invention on the dotted line $x-x$ of Fig. 4 with the bail turned down and pressing upon the contents of the file. Fig. 2 is a corresponding view, enlarged, of the wall end of the file. Fig. 3 is a corresponding view to Fig. 2 with the bail shown thrown up. Fig. 4 is a plan view of Fig. 1 next to the wall end of the file.

The same letters of reference are used to indicate identical parts in all the figures.

I provide a tray or drawer of the usual construction of this class of files, composed of a bottom piece A, a front wall B, and side walls C, united together in the usual or any suitable manner, and upon the inner side of the wall B, adjacent to each of the side walls C, is a vertical

recess D, covered by a metal plate E, which 50 has a slanting top F, covering the top of the recess, as seen in Figs. 1, 2, and 3. Within each recess and bearing against the vertical portion of the plate E is a vertical plate G, whose upper end terminates in a hook a, projecting through a slot b in the inclined portion F. A coiled spring H has its lower end secured to a pin or stud c, projecting from the inner side of the plate E, and its upper end secured to a pin or stud d, projecting 60 from the inner side of the plate G. The hook a engages with and overlaps a horizontal member e of a crank-arm on the rear end of the retaining bail-piece I, and this crank-arm is bent rearward and then again parallel with 65 the member e to form a toggle member f, resting upon the incline F of the plate E. The contractile force of the spring H draws down the plate G and the bail-piece I, as seen in Figs. 1 and 2, and causes the latter to bear 70 upon the letters or other papers J, contained in the file.

When it is desired to inspect, remove, or introduce any papers, it is only necessary to raise the outer end of the bail-piece I to the 75 position shown in Fig. 3, whereupon, owing to the incline F of the plate E, a locking-toggle will be formed between the members e f and the vertical line of the plate E, which will prevent the spring H from drawing down 80 the bail member until said toggle-lock is broken by drawing the bail member forward until its member f has passed in rear of a plane at right angles to the incline F and which passes through the axis of the member 85 a, whereupon the spring H will be released and its contractile force will draw down the bail member and hold it securely upon the filed papers, as seen in Figs. 1 and 2. By this simple arrangement but very little movement is required of the plate G and very little expansion of the spring H in giving the wide sweep necessary to raise and lock the bail-piece I.

Having thus fully described my invention, 95 I claim—

In a file of the character described, the combination of the back wall B provided with

recesses D, the vertical plates E covering said recesses and having inclined portions F at their upper ends, the plates G behind the plates E and provided with hooks *a* projecting through apertures in the inclines F, the springs H connecting the plates E G, and the bail I provided with the double crank-arms

ef, the former engaging the hooks *a* and the latter bearing upon the inclines F, substantially as and for the purpose specified.

FRED W. TOBEY.
